FIG. 1.

FIG. 2.

INVENTOR

Ethel Eaton Stricker

UNITED STATES PATENT OFFICE

109,097

DESIGN FOR A HOUSECOAT

Ethel Eaton Stricker, New York, N. Y.

Application January 31, 1938, Serial No. 74,764

Term of patent 3½ years

To all whom it may concern:

Be it known that I, Ethel Eaton Stricker, a citizen of the United States of America, residing in New York city, in the Borough of Manhattan, county and State of New York, have invented a new, original, and ornamental Design for a Housecoat, of which the following is a specification, reference being had to the accompanying drawing, forming part thereof, wherein,

The characteristic feature of my design resides in the combination on the housecoat as shown, of the contrasting pipings on the front and rear waist sections, arranged in the particular manner disclosed.

I claim:

The ornamental design for a housecoat, substantially as shown and described.

ETHEL EATON STRICKER.
